US0D1107901S

(12) **United States Design Patent** (10) **Patent No.:** **US D1,107,901 S**
(45) **Date of Patent:** **** Dec. 30, 2025**

(54) **INJECTION DEVICE**(71) Applicant: **Halozyme, Inc.**, San Diego, CA (US)(72) Inventors: **Todd J. Leadens, II**, Maple Grove, MN (US); **Baylor Frantz**, Minnetonka, MN (US); **Scott Beacher**, St. Louis Park, MN (US); **Kevin Swanson**, Plymouth, MN (US); **Michael Travanty**, Wayzata, MN (US)(73) Assignee: **Halozyme, Inc.**, San Diego, CA (US)(***) Term: **15 Years**(21) Appl. No.: **29/956,134**(22) Filed: **Aug. 6, 2024**

D765,833 S 9/2016 Geert-Jensen
D770,038 S 10/2016 Ahlgrim

FIG. 1 is a front perspective view of an injection device showing our new design;
FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines depict portions of the injection device that form no part of the claimed design.
